UNITED STATES PATENT OFFICE.

LEWIS ORWIG, OF ST. LOUIS, MICHIGAN.

ANTISLIP DRILL-ROD DEVICE.

Application filed July 6, 1925. Serial No. 41,693.

This invention relates to a device especially designed for use in pulling drill rods, the primary object of the invention being to provide means which will grip the drill rod to prevent the same from slipping into the well when the pulling mechanism is released to again grip the rod to pull the same from the well.

An important object of the invention is to provide a device of this character which will be automatic in its operation and one wherein a wedging action will be set up between the walls of the inclined grooves of the body portion of the device and the gripping elements, by the frictional contact between the drill rod and gripping elements.

A still further object of the invention is the provision of a portable device of this character so constructed that it will be moved from place to place to accomplish its purpose.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a longitudinal sectional view through a gripping device constructed in accordance with the invention.

Figure 2 is a transverse sectional view taken on line 2—2 of Figure 1.

Referring to the drawing in detail, the reference character 5 indicates the body portion which is provided with a central bore 6 extending from end to end.

Intersecting the bore 6 are the bores 7 that extend from one end of the body portion 5 or upper end thereof to a point in spaced relation with the lower end of the body portion, the lower end of the bore being in the form of a curved wall 8 providing a rest for the balls 9 that act as the gripping elements of the device.

The balls 9 are slightly smaller than the

bore 7 in which they operate to the end that the balls 9 may move freely within the bores to the end that upon upward movement of the rod being pulled, and which in the present showing is indicated at 10, the wedging action between the balls 9 and walls of the bore 7, will be broken allowing the rod 10 to move upwardly, but upon downward movement of the rod 10 the balls will be carried to the lower portions of the bores 7 gripping the rod and holding the same suspended.

As shown by Figure 1 of the drawing, the bores 7 are arranged at oblique angles with respect to the outer edges of the body portion 5 so that the wedging action as described will take place.

Positioned on the upper end of the body portion 5 is a cover plate 11 held in position by means of screws 12 to the end that the upper ends of the bores 7 may be opened to allow the balls 9 to be removed and replaced should they become damaged or otherwise rendered inoperative.

In the use of the device, the body portion 5 is positioned on the drill rod to be pulled, and is disposed adjacent to the mouth of the well. The usual pulling mechanism not shown, is now positioned on the rod 10 when the rod 10 is elevated, until the next adjacent section of the rod is elevated above the well, whereupon the uppermost section is unscrewed from the lower section.

When the sections are disconnected, the lower section will move slightly downwardly setting up a binding action between the balls 9 and the walls of the bores in which they are moved to hold the lower rod against further downward movement and retaining the same in such position that the pulling mechanism may be readily secured to the rod for a further pulling of the rod.

I claim:

In a device of the character described, a body portion having a central bore extending therethrough, said body portion having a plurality of bores extending at oblique angles with respect to the outer wall of the body portion, the last mentioned bores communicating with the first mentioned bore, said last mentioned bores having their inner end

100

walls curved and spaced from the outer end of the body portion to provide curved supporting surfaces, a plurality of balls disposed within the last mentioned bores and adapted to normally rest on the inner end walls of the bores, said balls adapted to grip a rod positioned within the central bore, and

a removable cover plate positioned over the body portion and adapted to close the upper ends of the angularly disposed bores.

10

In testimony that I claim the foregoing as my own, I have hereto affixed my signature.

LEWIS ORWIG.
